[57] CLAIM

The ornamental design for a combined can handle and opener, as shown and described.

DESCRIPTION

FIG. 1 is a front elevational view of a combined can handle and opener showing my new design;

FIG. 2 is a side elevational view thereof;

FIG. 3 is a rear elevational view thereof;

FIG. 4 is a top plan view thereof;

FIG. 5 is a bottom plan view thereof;

FIG. 6 is a front elevational view of a second embodiment of the combined can handle and opener shown in FIG. 1;

FIG. 7 is a side elevational view thereof;

FIG. 8 is a rear elevational view thereof;

FIG. 9 is a top plan view thereof; and

FIG. 10 is a bottom plan view thereof.
